Primary Examiner—Holly H. Baynham

(74) Attorney, Agent, or Firm—Grace J. Fishel

(57) **CLAIM**

The ornamental design for a lifting bracket, as shown and described.

DESCRIPTION

FIG. 1 is rear perspective view of a lifting bracket;

FIG. 2 is front elevation;

FIG. 3 is a rear elevation;

FIG. 4 is a right side elevation; the left side being a mirror image;

FIG. 5 is a bottom view; and,

FIG. 6 is a top view.

The broken line showing of openings and a bracket is included for the purpose of illustrating environment and forms no part of the claimed design.
